UNITED STATES PATENT OFFICE.

ORLANDO G. DARLING AND HENRY A. SCHULZ, OF BROOKLYN, N. Y.

TRUSS.

SPECIFICATION forming part of Letters Patent No. 293,231, dated February 12, 1884.

Application filed March 16, 1883. (No model.)

To all whom it may concern:

Be it known that we, ORLANDO G. DARLING and HENRY A. SCHULZ, of Brooklyn, in the county of Kings and State of New York, have 5 invented a new and useful Improvement in Trusses, of which the following is a full, clear, and exact description.

Reference is to be had to the accompanying drawings, forming part of this specification, in 10 which similar letters of reference indicate corresponding parts in all the figures.

Figure 1 is a perspective view of a truss to which our improvement has been applied. Fig. 2 is a side elevation of a part of the same, 15 partly in section through the line *xx*, Fig. 1. Fig. 3 is a sectional plan view of a part of the same, taken through the line *yy*, Fig. 2.

The object of this invention is to allow truss-pads to yield to the movements of the bodies 20 of their wearers without producing a friction upon the said bodies.

The invention consists in a truss constructed with a spring connected with the band of the truss, and resting against the hinged pad to 25 hold the said pad to its place, while allowing it to move with the movements of the body of the wearer. Between the end of the truss-band and the end of the pad-spring is interposed a block to raise the said upper end of the spring 30 out of contact with the hinged pad. To the lower part of the pad is attached a keeper, through which the pad-spring passes to keep the said spring and pad in contact, while allowing them to play freely upon each other, 35 as will be hereinafter fully described.

A represents the band or spring of the truss, to one end of which is attached a pivot, B, upon which is hinged the upper end of a pad, C, so that the said pad will be free to move 40 out and in to conform to the movements of the body of the wearer.

To the end of the band A is attached, or upon it is formed, a block, D, to which is secured by screws or rivets the upper end of a spring, E, so that the said upper end of the 45 spring will be raised out of contact with the upper end of the pad, and thus will not interfere with the movements of the said pad. The spring E extends downward along the outer side of the pad C, and is curved so that its 50 lower end will rest and press against the lower part of the said outer side of the said pad, as shown in Figs. 1 and 2. The lower end of the spring E is kept in place upon the lower part of the pad C by a keeper, F, attached to the 55 said pad, and through which the said spring passes, as shown in Figs. 1, 2, and 3, so that the said keeper will not interfere with the free movement of the said pad and spring upon each other. To the other end of the band A 60 is attached a strap, G, which is perforated to receive a pin, H, attached to the end of the band A or to the block D.

Having thus described our invention, we claim as new and desire to secure by Letters 65 Patent—

In a truss, the combination, with the band provided with the headed pivot projecting from one end thereof, and with the block or shoulder arranged at one side of said end, of 70 the pad hung upon the said pivot, and the flat spring secured to the block or shoulder, and projecting through a keeper of the pad and bearing against the latter, essentially as shown and described, and for the purpose set forth. 75

ORLANDO G. DARLING.
HENRY A. SCHULZ.
